COMBINED DESK TRAY AND PEN HOLDER

Roy O. Edwards, 8041 Taylor Ave.,
Huntington Beach, Calif. 92646

Filed May 25, 1965, Ser. No. 85,450

Term of patent 14 years

(Cl. D74—9)

The essential features of the design reside in the portions shown in solid lines.

I claim:

The ornamental design for a combined desk tray and pen holder, as shown and described.
